LEANDER BURDICK, H. J. CHASE, F. P. ISHERWOOD, AND W. S. ISHERWOOD, OF TOLEDO, OHIO.

Letters Patent No. 91,601, dated June 22, 1869.

TOBACCO-DRIER.

The Schedule referred to in these Letters Patent and making part of the same.

To all whom it may concern:

Be it known that we, LEANDER BURDICK, H. J. CHASE, F. P. ISHERWOOD, and W. S. ISHERWOOD, all of Toledo, in the county of Lucas, and State of Ohio, have invented a new and improved Process for Curing Tobacco; and we do hereby declare that the following is a full, clear, and exact description thereof, reference being had to the accompanying drawings, making part of this specification, in which—

Figure 1 is a longitudinal section, taken in the vertical plane Y Y, through an apparatus which is adapted for use in conducting our improved process.

Figure 2 is a section taken transversely through the apparatus in the vertical plane x x.

Similar letters of reference indicate corresponding parts in the two figures.

This invention relates to an improvement on the treatment of tobacco in the leaf, for the purpose of depriving it of those juices which, if allowed to remain in its cells, would cause it to mold and become sour, and give to it an unpleasant taste and odor. This treatment is termed sweating, or curing, and, as hitherto conducted, it is a long and expensive process, the success of which depends upon the condition of the weather.

The nature of our invention consists in subjecting tobacco to the action of artificial heat, ranging from 90° to 110° Fahrenheit, by enclosing the tobacco within a chest, which is surrounded by a jacket or external case, into which latter steam is conducted, said chest being provided with an outlet for the escape of the juices, which are expelled from the leaves in the form of vapor, and also with one or more perforated pipes, for allowing more or less steam to enter the chest during the process, as will be hereinafter explained.

To enable others skilled in the art to understand our invention, we will describe one practical mode of conducting the process.

In the accompanying drawings—

A represents a box or case, which may be made of any suitable capacity, and which is provided with a tightly-fitting movable cover, for allowing access to its interior when required.

B is a chest, made somewhat smaller in every direction than case A, and also provided with a tightly-fitting movable cover.

This chest B is arranged within the case A, so as to leave a space, a, surrounding it, into which space steam is admitted through pipe c, from any suitable generator.

We prefer to make the case A of wood, or other heat non-conducting material, for preventing undue radiation of heat; and also to make the interior chest of wood, or other similar material, to prevent liability of scorching the tobacco which is contained therein.

This chest B has a number of imperforated pipes, F, arranged at or near its bottom, and passing through it, which pipes are open at their extremities, for allowing steam from space a to circulate freely through them, and giving off a large amount of heat to the interior of the chest.

One of the pipes in chest B is thickly perforated, closed permanently at one end, and provided with a valve, g, at its opposite end, for closing this end when desired.

Valve g is applied on the inner end of a screw-rod, g', which passes through the outer case A, and is tapped through a fixed nut, h.

By means of pipe G and its valve, steam from space a can be introduced into the chest B, or prevented from entering this chest, as may be found necessary during the process.

A pipe, E, leads from the interior of chest B, through one of the walls of the case A, and conducts off all the vapor and disagreeable odor which rises from the tobacco.

s is a pipe which leads through the bottom of the case A, and conducts off the water of condensation from steam-space a.

In conjunction with this apparatus, two thermometers, C D, are employed for indicating the temperature, both in the chest B and in the steam-space a. The thermometers are applied in suitable chambers, formed on the case A, so as to be exposed to view during the process of treating the tobacco. The chamber enclosing the thermometer C communicates with the interior of the chest B, by means of the pipe d; and the chamber enclosing the thermometer D communicates with the steam-space a, by means of the pipe or orifice e, shown in fig. 1.

The tobacco to be treated is arranged loosely upon a frame within the chest B, and the cover of this chest, together with the cover of case A, are confined down tightly. Steam is then admitted into the space a, through pipe c, and the tobacco is thus subjected to heat ranging from 90° to 110° Fahrenheit, which temperatures will be indicated by the thermometers on the outside of case A, and should be maintained for several hours, or until the tobacco has been completely cured.

During this process a noxious vapor will escape from the interior of the chest through pipe E, which is produced by the evaporation of those juices in the tobacco that must be expelled before it is in a condition to be manufactured.

If at any time during the treatment it is desired to introduce steam directly into the chest, for moistening the tobacco and giving it darker shades of color, this can be done by adjusting valve g, and opening one end of pipe G.

We have found that leaves and stems of tobacco

may be given very dark shades by subjecting them to the action of steam; also that the heat which is applied to tobacco by means herein described, will sweat it rapidly and thoroughly, and in a short time expel the impurities which it is desired to get rid of, at the same time improve the quality of the tobacco for manufacturing purposes.

Having described our invention,

What we claim as new, and desire to secure by Letters Patent, is—

1. The method or process of sweating and curing tobacco, substantially as described.
2. In the process of sweating and curing tobacco, the employment of an apparatus consisting of a chest, B, enclosed by a case, A, so as to leave a steam-space, a,

pipes F G, and escape-pipe E, substantially as described.

Witness our hands, in matter of our application for a patent for improved mode of treating tobacco.
